PERFORATING GUN

Loyde H. Metzner, Los Angeles, Calif., assignor to
 Lane-Wells Company, Los Angeles, Calif., a cor-
 poration of Delaware

Application April 13, 1935, Serial No. 16,267

16 Claims. (Cl. 164—0.5)

This invention has to do in a general way with the art of perforating well casing and is more particularly related to improvements in perforators of the so-called "gun type."

5 The so-called "gun type" of casing perforator consists in a general way of a body member adapted to be lowered into the casing and having therein a transversely disposed cartridge or a plurality of such cartridges which are adapted 10 to be fired through the casing wall by means of an electric current conducted through suitable conductors to the cartridge from the surface of the ground. It is a primary object of this invention to produce a perforator of the general 15 class described which is provided with improved means for firing the cartridge or cartridges.

It is a further attending object of this invention to produce a perforator of the class described in which the cartridges or the cartridge is fired 20 by mechanical means carried by the perforator body and actuated by movements of the body which are controlled at the surface of the ground. Further in this connection, my invention contemplates a perforator which may be equipped 25 with any desired number of cartridges and in which the cartridges may be individually fired at any desired point along the line of the casing.

It is a further object of this invention to produce a device of the class described which is of 30 simple form and construction and which may be easily and quickly loaded and set with a minimum amount of danger to the operator.

The details in the construction of a preferred form of my invention, together with other objects attending its production, will be best understood from the following description of the accompanying drawing, which is chosen for illustrative purposes only, and in which

Fig. 1 is a sectional elevation with parts broken 40 away showing a section of casing with a preferred embodiment of my invention suspended therein;

Fig. 2 is an enlarged sectional elevation with parts broken away which is taken in a plane at right angles to the plane of Fig. 1 and illustrates 45 further details in the construction of a preferred embodiment of my invention;

Fig. 3 is a plan section taken along the line 3—3 of Fig. 2;

Fig. 4 is an enlarged fragmentary plan section 50 showing a portion of Fig. 3 and illustrating important details of the firing mechanism contemplated by this invention;

Fig. 5 is a fragmentary sectional elevation taken in a plane represented by the line 5—5 of 55 Fig. 4; and

Fig. 6 is a fragmentary outside elevation illustrating a modification of the construction contemplated by this invention.

More particularly describing the invention as herein illustrated, reference numeral 11 indicates a well casing within which a perforating member 12 is suspended by means of a cable or any other suitable means, indicated at 13.

The perforator 12 is shown as comprising an elongated substantially solid body or mandrel 15 having a rounded nose member 16 mounted on its lower end and provided with a connection 17 at its upper end whereby it is attached through the medium of a swivel joint 18 with a suspending bail member 19.

The body member 15 is provided with a plurality of longitudinally spaced inner chambers 22 which are adapted to receive and contain cartridge members 23 which are filled with explosive material indicated at 24. At the outer end of 20 each cartridge chamber 22 I provide an enlarged threaded recess 26 which receives a threaded plug member 27. The inner ends of the plug member 27 and that portion of the inner wall of the recess which surrounds the cartridge chamber 25 are preferably formed on the frustum of a cone so as to provide means for securely locking a diaphragm 29 composed of lead or other suitable material over the outlet or discharge end of the cartridge chamber. The plug 27 is provided

25 with a passage 30 formed in axial alignment with the cartridge chamber, such passage containing a projectile 31 and being closed against the ingress of pressure fluid by means of a button 33, composed of "Bakelite" or other suitable frangible 30 material, which is pressed into a recess 34 formed about the outer end of the passage 30. The plug 27 is provided with a slot 35 to facilitate its installation and the periphery of the plug is surrounded by a washer 36 composed of rubber or 35 other flexible material and channeled so as to be spread into engagement with the plug and the surrounding wall surface by the pressure of the fluid in the well.

For the purpose of firing the cartridge I provide the same with a percussion cap 40 behind which a firing pin 41 is slidably mounted in a suitably formed passage in the body. The rear end of the firing pin 41 extends into what I may term a hammer chamber 42 formed in the body 50 in substantial alignment with the cartridge chamber 22. The outer end of this hammer chamber 42 is shown as being enlarged and threaded as indicated at 43 for the reception of a screw plug 44. Formed on the inside of the screw plug 44 is 55

a recess 45 which receives the rear end of a guide pin 46 upon the forward end of which a plunger or hammer member 47 is mounted. This hammer member is adapted to be driven into engagement with the firing pin by means of a compression spring 48 and is normally held in retracted position by means of a trigger mechanism, a preferred form of which will now be described.

0 The trigger member contemplated by this invention comprises what I may term a cross member 50 which is shown as being rotatably mounted in a cylindrical bore 51 which extends from an undercut region 52 in the side wall of the body 5 into the body at substantially right angles to the hammer chamber 42. In the form shown the bore 51 is illustrated as being positioned with its axis above the axis of the hammer chamber 42 so that the cross member 50 will normally be interposed between the hammer member 47 and the outer end of the firing pin 41. The cross member 50 is shown as being provided with an undercut portion or recess 53, the radius of which is equal to or greater than the radius of the hammer chamber so that, when the cross member 50 is rotated or moved into a position at which the recess or undercut portion 53 falls into alignment with the hammer chamber, the hammer is released to be driven into engagement with the firing pin. This operation is indicated in broken lines in Fig. 5. The cross member 50 is shown as being mounted in the body member and retained therein by means of a rubber packing cone 56, such cone being provided with grooves 57 which are acted on by the pressure of the fluid in the well to pack the cross member securely in place.

For the purpose of moving or rotating the cross member 50 to release the hammer, and permit its driving the firing pin forward to fire the cartridge, I provide the end of the cross member 50, in this form of my invention, with a lever 60, such lever being contained in the undercut portion 52 and being normally positioned so as to extend substantially at right angles to the longitudinal body, 45 as clearly shown at 60n in Fig. 2.

For the purpose of swinging or turning this lever to its cartridge firing position, I provide the body member with a sleeve 63 which is slidably mounted thereon and has an inwardly extending projection or tongue 64 which rides in a groove 65, such groove communicating with the successive cut-away regions 52 and being in alignment with the respective levers 60. With this arrangement it will be seen that as the body member travels downwardly through the sleeve 63, the trigger or lever members 60 will be successively swung to discharge the respective cartridges as each lever is engaged by the tongue or projection 64.

0 In order to accomplish this, it is first necessary that the sleeve be held stationary with respect to the body when it is desired to fire the cartridges, and furthermore, in order to prevent all of the cartridges being fired through one spot, 5 and also to permit the firing of cartridges at any desired spot in the casing, it is necessary that means be provided for optionally locking the sleeve upon the body during at least one direction of movement of the body.

0 For the purpose of restraining the sleeve 63 against movement with respect to the body, I show the upper end portion of the sleeve as being provided with a unit composed of a plurality of friction spring members of any conventional type, 5 such spring unit being indicated generally by ref-

erence number 67, and being shown as having sliding frictional engagement with the interior of the casing. Since the friction between the spring members and the interior of the casing is much greater than the frictional resistance of the body to its movement through the sleeve, it will be seen that under normal circumstances this spring unit will hold the sleeve against movement with respect to the body.

For the purpose of optionally locking the sleeve 10 upon the body, so that downward movement of the body carries the sleeve with it, I show the sleeve as being provided with an inwardly extending projection or a plurality of such projections indicated at 70. These projections are associated 15 with a plurality of longitudinal grooved sections 71. The longitudinal sections 71 and the pin 70 are positioned so that the pin is traveling through a longitudinal section during such time as the projection or lip 64 is traveling through that portion of the groove 65 which contains the trigger member 60. In other words, each time the body is aligned so that the pin 70 falls in the bottom portion of a grooved section 71, and is then permitted to travel downwardly, the finger 64 engages the trigger 60 and fires the cartridge at that particular point.

For the purpose of locking the sleeve against movement with respect to the body, I provide the bottom portion of each longitudinal grooved section 30 71 with an offset grooved section 72. This offset grooved section is shown as having a cam shoulder 73, the top point 74 of which is shown as being positioned to the left of the center line of the top of the offset section 72. With this arrangement it will be observed that when the pin 70 occupies the dotted line position at the top of the offset 72, as shown in Fig. 2, and the body member is lowered with the parts in such position, the sleeve will be moved with the body member to any desired point. As soon as the body member is raised again, however, the pin engages the cam surface 73 and is carried back into alignment with the next succeeding longitudinally extending slot 71, after which another 40 downward movement of the body permits the pin 70 to travel upwardly through the slotted section 71 and the finger member 64 to engage the trigger and fire that particular cartridge. As the body member is continued to be lowered after such a firing operation, the pin 70 is received in curved offset slot 75 located at the upper end of the longitudinal extension of the groove section, such curved groove 75 rotating the body and permitting the pin to be received in the upper end portion of the next offset 72. In order to permit the body being rotated in this manner, with respect to the finger 64 and its associated groove 65, it is necessary to provide the groove 65 with cut-away portions which are indicated 50 at 79.

The operation of the device contemplated by this invention may be briefly described as follows: Assuming the parts to be in the position shown in Fig. 2, in which the pin or pins 70 are 65 contained in the lowermost offset groove 72, the device is lowered downwardly into the well, the sleeve being carried with the body and being located at the lowermost end thereof. When the device has been lowered to the point at which 70 perforating operations are to be started, the first operation is to raise the body a slight distance by means of the suspending cable 13 and then lower the same again. This lowering movement, as has been pointed out, is effective to fire the first 75

cartridge, but it will fire no more since the continued lowering movement of the body brings the next offset slot 72 into engagement with the pin 70, and continued lowering movements merely carries the sleeve to a lower position in the casing. The position of the next perforation may be changed in this manner or it may be obtained by then pulling the body upwardly to bring the bottom of the next longitudinal grooved section 71 into engagement with the pin 70, and continued upward movement will raise the sleeve to any desired point in the casing, after which another lowering of the body is effective to fire the next cartridge. It will thus be seen that the position of the perforations in the casing may be located either above or below the position of the perforation which has been fired next previous to that which is to be fired.

As an added precaution to insure the movement of the pin 70 from the offset groove 72 and to the longitudinal groove section 71, I show in Fig. 6 a modified form of the invention in which the offset section indicated at 72' is shown as being provided with spring fingers 80 and 81 adapted to guide the pin during its successive movements. The arrows in Fig. 6 indicate the travel of the pin during the successive opposite movements of the body with respect to the sleeve, or, since the pin actually remains stationary, these arrows more specifically indicate the movement of the grooves with respect to the pin.

It is to be understood that while I have herein described and illustrated one preferred form of the invention, the invention is not limited to the precise construction described above but includes within its scope whatever changes fairly come within the spirit of the appended claims.

I claim as my invention:

1. An apparatus for perforating well casing embodying: a body adapted to be suspended in the casing and having a transverse chamber therein; a cartridge in said chamber adapted to be fired through said casing; a sleeve member on said body; means associated with said sleeve and operative during relative movement between said sleeve and said body for firing said cartridge; means on said sleeve engaging the interior of said casing for restraining said sleeve against movement relative to said casing; and releasable means for locking said sleeve on said body.

2. An apparatus for perforating well casing embodying: a body adapted to be suspended in the casing and having a transverse chamber therein; a cartridge in said chamber adapted to be fired through said casing; a sleeve member on said body; means associated with said sleeve and operative during relative movement between said sleeve and said body for firing said cartridge; means on said sleeve engaging the interior of said casing for restraining said sleeve against movement relative to said casing; and releasable means interposed between said sleeve and said body for controlling the longitudinal movements of said body relative to said sleeve.

3. An apparatus for perforating well casing embodying: a body adapted to be suspended in the casing and having a transverse chamber therein; a cartridge in said chamber adapted to be fired through said casing; a sleeve member on said body; means associated with said sleeve and operative during relative movement between said sleeve and said body for firing said cartridge; means on said sleeve engaging the interior of said casing for restraining said sleeve against movement relative to said casing; and

a projection in said sleeve adapted for reception in a longitudinal groove in said body, thereby permitting downward movement of said body through said sleeve, said groove having an offset portion at its lower end adapted to engage said projection and limit the downward movement of said body relative to said sleeve. 8

4. An apparatus for perforating well casing embodying: a body adapted to be suspended in the casing and having a transverse chamber 10 therein; a cartridge in said chamber adapted to be fired through said casing; a sleeve member on said body; means associated with said sleeve and operative during relative movement between said sleeve and said body for firing said cartridge; 15 means on said sleeve engaging the interior of said casing for restraining said sleeve against movement relative to said casing; and a projection in said sleeve adapted for reception in a longitudinal groove in said body, thereby permitting 20 downward movement of said body through said sleeve, said groove having an offset portion at its lower end adapted to engage said projection and limit the downward movement of said body relative to said sleeve, and said offset portion 25 having a cam surface adapted to engage said projection and direct the same into said longitudinal groove during an upward movement of said body.

5. In an apparatus for perforating casing, the 30 combination of: a body adapted to be suspended in said casing and having a transverse chamber therein; a cartridge in said chamber adapted to be fired through the wall of said casing; mechanical means for firing said cartridge; a sleeve 35 member slidably mounted on said body; means on said sleeve operative during longitudinal movement of said body relative thereto for actuating said firing means; movement restraining means mounted on said sleeve and engaging said 40 casing; and means interposed between said body and said sleeve for controlling the longitudinal movement of said body relative to said sleeve.

6. In an apparatus for perforating casing, the 45 combination of: a body adapted to be suspended in said casing and having a transverse chamber therein; a cartridge in said chamber adapted to be fired through the wall of said casing; mechanical means for firing said cartridge; a sleeve member slidably mounted on said body; means 50 on said sleeve operative during longitudinal movement of said body relative thereto for actuating said firing means; movement restraining means mounted on said sleeve and engaging said casing; and means interposed between said body 55 and said sleeve for controlling the longitudinal movement of said body relative to said sleeve, said last mentioned means comprising a projection in said sleeve adapted for reception in a longitudinal groove in said body, said groove 60 having an offset portion at its lower end adapted to engage said projection and limit the downward movement of said body relative to said sleeve.

7. In an apparatus for perforating casing, the 65 combination of: a body adapted to be suspended in said casing and having a transverse chamber therein; a cartridge in said chamber adapted to be fired through the wall of said casing; means for firing said cartridge; a sleeve member slidably mounted on said body; means on said sleeve operative during longitudinal movement of said body relative thereto for actuating said firing means; movement restraining means mounted on said sleeve and engaging said casing; means in- 75

terposed between said body and said sleeve for controlling the longitudinal movement of said body relative to said sleeve, said last mentioned means comprising a projection in said sleeve adapted for reception in a longitudinal groove in said body, said groove having an offset portion at its lower end adapted to engage said projection and prevent downward movement of said body relative to said sleeve; and means for rotating said body to swing said projection from said offset into alignment with said longitudinal groove.

8. In a perforator of the class described the combination of a longitudinal body having a transverse cartridge chamber; a cartridge in said cartridge chamber; a firing pin mounted in said body for firing said cartridge; a hammer adapted to actuate said firing pin; trigger means for releasably holding said hammer in a retracted position; a sleeve member slidably mounted on said body for actuating said trigger to release said hammer; means for restraining the movement of said sleeve; and means operative during unidirectional movement of said body for locking said sleeve to said body; said last mentioned means comprising a projection in said sleeve adapted for reception in a longitudinal groove in said body, said groove having an offset portion at its lower end adapted to engage said projection and prevent upward movement of said body relative to said sleeve; and cam means in said offset portion adapted to swing said projection into alignment with said longitudinal groove during an upward movement of said body through said sleeve.

9. In a casing perforator of the class described the combination of: a longitudinal body adapted to be lowered into said casing and having a transverse cartridge chamber therein; a cartridge in said cartridge chamber; a firing pin slidably mounted in said body behind said cartridge chamber; a hammer chamber formed in said body behind said firing pin in axial alignment therewith; hammer means slidably mounted in said hammer chamber; a cross pin rotatably mounted in said body across said hammer chamber between said firing pin and said hammer to releasably hold the latter in a retracted position, said cross pin having a cut-out portion adapted for alignment with said hammer chamber to release said hammer; means for imparting segmental rotation to said cross member to align said cut-out portion with said hammer chamber and release said hammer; and sealing means interposed between the outer end portion of said cross member and said body.

10. In a casing perforator of the class described the combination of: a longitudinal body adapted to be lowered into said casing and having a transverse cartridge chamber therein; a cartridge in said cartridge chamber; a firing pin slidably mounted in said body behind said cartridge chamber; a hammer chamber formed in said body behind said firing pin; hammer means mounted in said hammer chamber; a cross member mounted in said body between said firing pin and said hammer to releasably hold the latter in a retracted position and means for actuating said cross member to release said hammer; said last mentioned means including a sleeve member slidably mounted on said body adapted to frictionally engage the interior of the casing.

11. In a casing perforator of the class described the combination of: a longitudinal body adapted to be lowered into said casing and having a transverse cartridge chamber therein; a cartridge in

said cartridge chamber; a firing pin slidably mounted in said body behind said cartridge chamber; a hammer chamber formed in said body behind said firing pin and in substantially axial alignment therewith; hammer means mounted in said hammer chamber; sealing means in the outer end of said hammer chamber, a cross member rotatably mounted in said body between said firing pin and said hammer to releasably hold the latter in a retracted position; said cross member having a cut away position adapted for alignment with said hammer chamber; means for shifting said cross member to align said cut-away position with said hammer chamber and thereby release said hammer; and sealing means interposed between the outer end portion of said cross pin and said body.

12. In a casing perforator of the class described the combination of: a longitudinal body adapted to be lowered into said casing and having a transverse cartridge chamber therein; a cartridge in said cartridge chamber; a firing pin slidably mounted in said body behind said cartridge chamber; a hammer chamber formed in said body behind said firing pin; hammer means mounted in said hammer chamber; sealing means in said hammer chamber behind said hammer, a cross member rotatably mounted in said body between said firing pin and said hammer to releasably hold the latter in a retracted position; said cross member having a cut-away position adapted for alignment with said hammer chamber; means for rotating said cross member to align said cut-away position with said hammer chamber and thereby release said hammer; said last mentioned means including a lever on said cross member, and a sleeve member on said body adapted to engage and swing said lever during relative longitudinal movement of said body through said sleeve; and sealing means interposed between the outer end portion of said cross member and said body.

13. In a casing perforator of the class described, the combination of: an elongated body adapted to be lowered into said casing; a sleeve member slidably mounted on said body; restraining means on said sleeve adapted to engage the interior of said casing; a plurality of longitudinally spaced and transversely disposed cartridges mounted in said body; cartridge firing means in said body associated with each cartridge; a trigger member for independently releasing each of said firing means; and means on said sleeve for actuating the successive trigger members.

14. In a casing perforator of the class described, the combination of: an elongated body adapted to be lowered into said casing; a sleeve member slidably mounted on said body; restraining means on said sleeve adapted to engage the interior of said casing; a plurality of longitudinally spaced and transversely disposed cartridges mounted in said body; cartridge firing means in said body associated with each cartridge; a trigger member for independently releasing each of said firing means; means on said sleeve for actuating the successive trigger members; and means for controlling the longitudinal movement of said body relative to said sleeve.

15. In a casing perforator of the class described, the combination of: an elongated body adapted to be lowered into said casing; a sleeve member slidably mounted on said body; restraining means on said sleeve adapted to engage the interior of said casing; a plurality of longitudinally spaced and transversely disposed car-

tridges mounted in said body; cartridge firing means in said body associated with each cartridge; a trigger member for independently releasing each of said firing means; means on said sleeve for actuating the successive trigger members; and means interposed between said sleeve and said body, and operative by opposite longitudinal movements of said body for controlling the movement of successive trigger bearing sections of said body relative to said sleeve.

5. 16. In a casing perforator of the class described, the combination of: a longitudinal body adapted to be lowered into said casing and having a transverse cartridge chamber therein; a cartridge in 10 said cartridge chamber; a firing pin slidably mounted in said body behind said cartridge chamber; a hammer chamber formed in said

body behind said firing pin in axial alignment therewith; a plunger hammer in said hammer chamber; sealing means in the outer end of said hammer chamber; spring means engaging said hammer for driving same into engagement with 5 said firing pin; and means for releasably holding said hammer in a retracted position comprising a cross member rotatably mounted in said body at substantially right angles with said hammer chamber and extending therethrough between 10 the retracted position of said hammer and said firing pin, said cross member having a cut out portion adapted for alignment with said hammer chamber to release said hammer, and means for rotating said cross member to release said hammer. 15

LOYDE H. METZNER.
